METHOD OF AND RACK FOR STORING
LUMBER

Leland A. Pace, El Monte, Calif.

Application December 26, 1939, Serial No. 310,870

3 Claims. (Cl. 211—49)

This invention relates generally to the lumbering industry, and more particularly to the yard storage of sized lumber as received from mills.

It is the present practice in lumber yards to stack milled lumber solidly in racks wherein the pieces of lumber are laid horizontally one upon the other, with the result that a considerable portion of the lumber, although received straight and true, from the mill, gradually becomes warped and/or twisted, so as to render it unsalable as first grade lumber.

This defective portion of the lumber represents a considerable financial loss to the dealer, as such lumber must be sold at reduced prices, or cut into shorter lengths to eliminate crooked portions, which latter can only be sold for fuel.

It is the object of this invention to provide a method of and rack for storing lumber which eliminates the afore-mentioned defective portion of lumber and its attendant financial loss, and substitute therefor, among many advantages, the following:

1. Insures that all pieces of straight lumber will remain straight and in a fresh condition;
2. Straightens crooked and otherwise deformed lumber which is received green or is wetted;
3. Reduces labor in stacking lumber, and eliminates labor and attendant loss of time in picking out straight pieces from crooked ones when removing lumber from rack to fill an order;
4. Saves space otherwise necessarily devoted to the storage of crooked lumber culled from present type racks in selecting lumber to fill orders.

With these and other objects in view, the invention resides in the method and in the combinations and arrangements of elements as set forth in the following specification, and particularly pointed out in the appended claims.

In the accompanying drawings,

Figure 1 is a view in side elevation of a lumber rack embodying this invention, and by which the method involved in the invention can be practiced;

Figure 2 is a view of the lumber rack in front elevation;

Figure 3 is a fragmentary bottom plan view of the lumber rack.

In carrying the invention into practice, a rack is constructed of suitable material such as wooden beams to provide a number of built-up horizontal base members 10 spaced apart in parallelism and resting on the ground or suitably secured to the floor of a lumber yard. Rising from the members 10 medially between their ends are vertical members 11 which are secured to the

members 10 by a tie rod 12 passing through openings in the members and having nuts 13 at their ends.

Adjacent their ends the base members 10 are provided with longitudinal slots 14 through which pass bolts 15 having nuts 16 for adjustably clamping the lower ends of pairs of other vertical members 17 to the horizontal members with the latter interposed between the pairs as shown in Figure 2. The pairs of vertical members 17 can thus be adjusted towards and away from the intermediate vertical members 11 to vary the horizontal distance therebetween.

At their upper ends, the vertical members 17 are adjustably connected to the vertical members 11 by sectional tie rods 18 having turnbuckles 19 connecting the two rod sections, one of the latter of which is rigidly secured to the vertical members 11 by braces 20, all as clearly shown in Figure 1. Thus, the upper ends of the vertical members 17 can be adjusted towards and away from the intermediate vertical members 11 to vary the horizontal distance therebetween.

The upper ends of the vertical members 11 and 17 are connected by horizontal cross members 21 and 22, respectively, and by oblique braces 23 and 24, respectively, to stiffen the structure laterally. Additional bracing and supports can be provided in accordance with the loads of lumber to be stored in the rack.

Pivottally mounted on the tie rod 12 for angular adjustment parallel to a vertical plane to occupy various selected inclined positions are bottom or floor forming members 25 which extend between the pairs of vertical members 17 and rest upon bolts 27 which support the members 25 at pre-calculated angles with respect to the horizontal. Wing nuts 28 are threaded on the bolts to clamp the members 25 against displacement and to enable the bolts to be readily changed from one to another of a series of openings 29 provided in the pairs of vertical members 17 at precalculated intervals along the lengths thereof.

In practice, the angles at which the members 25 are supported are calculated in accordance with the proportions of the cross sectional dimensions of a particular standard size of lumber which is to be stored in a compartment of the rack, all in such manner that the horizontal and vertical components resulting from the force of gravity acting upon the pieces of lumber when stacked in the rack as shown in the drawings will be in direct proportion to the width and thickness of the pieces of lumber.

Thus, for example, if pieces of lumber whose

width and thickness are proportioned two to one such as 1 x 2's, 2 x 4's and 3 x 6's, and with the pieces placed on the bottom forming members 25 with the larger of the two dimensions in parallelism with these members as shown in Figure 1, an angle of approximately 26½ degrees of the members 25 to the horizontal will result in resolving the force of gravity acting upon such sizes of lumber into two components, one of which is twice the magnitude of the other.

Therefore, the force of gravity will act equally in directions to urge each board against the preceding board placed in the same row, and against boards of the row immediately below, with the result that the boards will automatically stack in tight contact with each other both horizontally and vertically when placed in successive rows upon the members 25.

Therefore, it will be clear that boards placed in the rack in a straight condition will be maintained straight by virtue of their weights being imposed directly upon each other in horizontal and vertical directions instead of in a vertical direction alone as results from stacking of lumber in horizontal racks heretofore proposed. Should green lumber which is warped or twisted be placed in the rack, such lumber will be straightened as the pieces automatically pack closely against one another. The straightening of seasoned lumber can be effected by wetting the lumber and placing same in the rack.

In the operation of stacking lumber, the preferred method is to adjust the members 25 in accordance with the size of lumber to be stacked, by suitable adjustment of the supporting bolts 27, following which a single operator successively places pieces of lumber across the members. As each piece is placed, it naturally slides transversely towards the lowest end of the member 25, so that the pieces automatically align themselves, with the first piece abutting the intermediate vertical members 11. A predetermined number of pieces are placed to form the first row, after which suitable adjustment of the members 17 is made, if necessary to bring them in contact with the last placed piece of the first row and in parallelism with the members 11.

Other pieces are similarly placed to form additional rows until the desired quantity has been stacked. The several rows will be confined between the members 11 and 17, and the individual pieces will be tightly packed and will be maintained in a fresh condition.

It will be noted from a consideration of Figure 2 that the stack of lumber also inclines slightly in a direction longitudinally of the pieces so as to insure that rain water will tend to drain to one low corner of the stack.

It will be appreciated from the foregoing description that the method of stacking lumber as

involved in this invention effects a saving in labor and time as well as insures that straight lumber will be maintained straight, and crooked green lumber or crooked seasoned lumber which has been wetted will be straightened automatically due to the manner in which the weight of the pieces is divided into substantially equal horizontal and vertical components so that force is exerted horizontally as well as vertically by each piece upon another.

What is claimed is:

1. A rack for the storage of sized lumber comprising: a plurality of spaced vertical members; bottom forming members spanning said vertical members in an inclined position for the storing of pieces of lumber in superposed rows on the bottom forming members; and means by which the horizontal distance accommodating pieces of lumber between said vertical members can be varied to enable pieces of lumber to be confined snugly against each other on the bottom forming members between the vertical members to facilitate straightening of crooked pieces of lumber.

2. A rack for the storage of sized lumber comprising: a plurality of vertical members arranged in pairs; a second plurality of vertical members spaced from the first said members; base members connecting the pluralities of members; upper members connecting the pluralities of members; bottom forming members spanning said pluralities of members and having one end projecting between said pairs of the latter; means pivotally mounting the other end of the bottom forming members; means for supporting said one end of the bottom forming members to dispose the latter at a precalculated angle for the purpose described; and means by which said pluralities of vertical members are rendered adjustable towards and away from each other to accommodate a predetermined number of pieces of lumber on the bottom forming members.

3. A rack for the storage of sized lumber comprising: a plurality of vertical members arranged in pairs; a second plurality of vertical members spaced from the first said members; base members connecting the pluralities of members; upper members connecting the pluralities of members; bottom forming members spanning said pluralities of members and having one end projecting between said pairs of the latter; means pivotally mounting the other end of the bottom forming members; means for supporting said one end of the bottom forming members to dispose the latter at a precalculated angle for the purpose described; and means by which the inclined position of the bottom forming members can be varied to accommodate differently proportioned cross sectional dimensions of lumber.
